UNITED STATES PATENT OFFICE.

HARRY C. GODDARD, OF ROLFE, IOWA.

ATTACHMENT FOR TYPE-WRITERS.

1,163,906.

Specification of Letters Patent.

Patented Dec. 14, 1915.

Application filed December 16, 1914. Serial No. 877,571.

To all whom it may concern:

Be it known that I, HARRY C. GODDARD, a citizen of the United States, residing at Rolfe, in the county of Pocahontas, State 5 of Iowa, have invented certain new and useful Improvements in Attachments for Type-Writers; and I do hereby declare the following to be a full, clear, and exact description of the invention, such as will enable 10 others skilled in the art to which it appertains to make and use the same.

This invention relates to an attachment for typewriters and especially for an attachment to return the carriage to its starting 15 position and at the same time rotate the roll so that a new line may be started.

An object of the invention is to provide a structure which will accomplish this result without necessitating the removal of the 20 hands of the operator from the keyboard.

A further object of the invention is to so construct the device that it may be readily applied to the typewriters of the construction used at the present time without modifying 25 the carriage control but will be attached to the operating handle of the said carriage control.

With these and other objects in view, such as will appear as the description progresses, my invention comprises the combination 30 and arrangement of parts such as set forth in and falling within the scope of the appended claim.

Referring to the drawing: Figure 1 is an 35 end elevation of a conventional representation of a typewriter showing my attachment mounted thereon. Fig. 2 is a plan view of the same. Fig. 3 is a rear elevation showing the shifting bar in the position it will occupy when the carriage begins its movement. Fig. 4 is a perspective view of the combined 40 pulley support and guide. Fig. 5 is a sectional view showing the manner of attaching the connecting link to the ordinary shifting handle. Fig. 6 is a detail elevation 45 of the key board operating lever which is located on the key board. Fig. 7 is an elevational view of the other guide for the shifting arm. Fig. 8 is a perspective view 50 of the lever for actuating the flexible members which are attached to the shifting arm.

Referring to the drawing by reference characters wherein like parts are indicated by like characters throughout the several 55 views: The reference character 1 indicates

the frame of a typewriter, 2 the paper roll and 3 the carriage on which the said roll is mounted.

The reference character 4 indicates the shifting handle for the carriage and roll, 60 and this handle is of the ordinary type wherein the carriage is shifted at the same time the roll is rotated a space. In order that this carriage may be shifted, and the roll turned without the operator lifting his 65 hands from the keyboard, I have provided a lever 5 which is pivotally mounted on the side bar 6 of the keyboard of the machine. Secured to the lower end of this lever 5 is a link 7 which extends rearwardly to the 70 side of the frame of the machine, and is connected at its other end as at 8 to a second lever 9, the latter being pivoted between its end as at 10. To the lower end of this lever 9 is secured a flexible member 11 which 75 passes over a small pulley 12 on the side of the frame 1. This flexible member is secured as at 13 to the periphery of a disk 14, which disk is formed integral with a relatively larger disk 15, the said disk being 80 rotatably mounted on a projection 16 on a bracket 17, the latter having an inwardly extending arm 18 on the lower end thereof which is secured to the rear bar 19 of the frame 1. On a projection 20 of this bracket 85 is rotatably mounted a pulley 21. A flexible member 22 is secured at 23 to the periphery of the disk 15, and this flexible member passes over the pulley 21 and over an additional pulley 24 which is rotatably mounted on a projection 25 on the bracket 17. This flexible member is then extended and 90 is secured to the end of the shifting arm 26, as at 27. This shifting arm is angular in formation and extends completely across the 95 back of the frame 1 then forwardly and parallel to the side of the said machine, and is guided by a U-shaped member 27 on the upper end of the bracket 17 and a guide member 28 which is secured to the side bar 100 29 of the frame 1. This guide 28 comprises an upper member 30 which extends through an opening 31 in the arm 26, and a lower member 32 which bears on the lower face of the said arm 26. Secured to the end of the 105 forwardly extending portion of the member 26, is a shifting link 33 which extends transversely across the machine and is secured at its other end to the carriage shifting lever 4 in a manner shown in Fig. 5 of the drawing. 110

In operation when it is desirable to return the carriage to its initial position and to also rotate the roller 2 so that a new line may be started, the operator engages the handle 5 on the upper end of the lever 5 and pushes the handle from him, and thus through the link 7 and the lever 9 pulls the flexible member 11 about the pulley 12 and consequently through the aforementioned mechanism 10 draws the end of the arm 26 toward the pulley 25 and thus the shifting link 33 transversely across the machine and with it the carriage 3. At this time the carriage is moved to its initial position and the roller 15 2 rotated in the usual manner through the handle 4. As the carriage returns to its initial position the tendency of the flexible members 11 and 22 is to slack and in order that these may be maintained taut as the 20 carriage moves across the machine, I have provided a coil spring 34 which is connected to the lever 5 and to the side bar 6 of the keyboard.

From the foregoing description it will be 25 readily appreciated that I have provided a device that may be secured to the operating handle of a carriage of the ordinary typewriter, and by means of which the carriage may be shifted to its position and at the 30 same time the paper carrying roller turned and I have so constructed the device that the operating lever therefor will be located adjacent the keyboard so that it will not necessitate the operator lifting his hands 35 from the keyboard, and consequently the shifting of the carriage to its initial position

may be very readily and quickly accomplished.

While I have illustrated and described a particular embodiment of my invention, I 40 have merely done so for the sake of convenience, and I do not wish to be limited to that particular embodiment, as it is obvious that numerous changes may be made in the details of construction without departing 45 from the spirit of the invention or exceeding the scope of the appended claim.

What is claimed is:—

The combination with a typewriter having a carriage shifting and roll turning handle, of a link detachably connected thereto, a shifting arm connected to one end of the said link and extending backwardly and across the rear of the said typewriter, guides for said arm, a bracket secured to the lower rear bar of the said typewriter, a lever secured to the side of the said typewriter, a flexible member secured to the one end of the said shifting arm and having connection to the said lever, a second lever operatively connected to the first mentioned lever and constructed and arranged to actuate the shifting arm, the said lever being located adjacent the keyboard of the typewriter, and resilient means for maintaining the said flexible means taut.

In testimony whereof, I affix my signature, in the presence of two witnesses.

HARRY C. GODDARD.
